UNITED STATES PATENT OFFICE

FREDERICK C. OVERBURY, OF HILLSDALE, NEW JERSEY, ASSIGNEE, BY MESNE ASSIGNMENTS, TO THE PATENT AND LICENSING CORPORATION, OF BOSTON, MASSACHUSETTS, A CORPORATION OF MASSACHUSETTS

ROOFING ELEMENT

Application filed May 12, 1928. Serial No. 277,133.

My invention relates to roofing and has more particular relation to flexible roofing elements made of asphalt saturated and coated and mineral surfaced roofing felt.

5 The principal object of my invention is to provide, in a shingle of this general type, means for securely holding down the weather exposed portion of each shingle upon the surfaces of the underlying shingles so as to preclude the blowing up or curling of the 10 exposed portions and the beating in of rain or snow beneath the shingles.

It is an important object of my invention also to provide a shingle of this character 15 having means for thus holding it in proper position on the roof, and constructed in such a way as to permit free movement of the fastened portion of the shingle during the movements accompanying expansion and contraction of the sub-structure.

20 In accordance with my invention, I form the shingle with a folded under corner adapted to underlie the main body portion of the shingle when in place on a roof, and arranged 25 for the ready application thereto of a fastening device which serves to securely clamp the undeturned corner in position and thereby effectively retain the exposed portion of the shingle in flatwise position over its sub- 30 jacent companion shingles. Further, in accordance with my present invention, the undeturned corner of the shingle is formed with notches in its marginal edges arranged to accommodate the fastening device, which 35 may be of any suitable metal, and which, when in position is totally concealed by the overlying main body portion of the shingle.

In the accompanying drawings I have illustrated several embodiments of my invention. 40 In these drawings,

Figure 1 shows a section of roofing laid up with shingles constructed in accordance with my invention,

45 Figure 2 is a face or plan view of a single shingle of my present invention,

Figure 3 is a detail, showing the location of the fastening device when in operative position,

50 Figure 4 is a fragmentary view showing

several shingles laid up with a modified form of fastening device,

Figure 5 is a detail in perspective of the form of fastening shown in use in Figure 4,

Figure 6 illustrates one mode in which the 55 shingles of my invention may be cut from a sheet of roofing felt.

Referring more in detail to Figures 1, 2, and 3, the numeral 11 indicates an individual shingle preferably formed, as shown, of rectangular configuration and having one of its corner portions, as at 12, adapted for retroversion along the line 13 so as to underlie the main body portion of the shingle, the shingle thus presenting a folded edge of considerable 60 thickness contributing to the enhancement of the shadow effects so desirable in this type of roof. The operation of folding the corner portion 12 beneath the main body of the shingle will preferably be performed after 65 the shingle has been severed from the finished sheet of roofing. This operation may be carried out in a very simple manner by the application of heat to the shingle in the region of the line of fold, and when the material in this region has been thus rendered sufficiently pliable for the purpose, any suitable mechanism may be employed for applying the bending force necessary to form the fold, whereupon the shingle may be allowed 70 to cool so as to regain its normal flexibility 75 with the flap 12 in its retroverted position.

Numerous schemes have been proposed for retaining in proper position on a roof a shingle having an underfolded flap as just 80 described, but these have either proved insecure or they have resulted in clamping or holding the flap so fixedly as to cause the shingle to bulge and buckle due to insufficient compensative movement during expansion and contraction of the sub-structure.

By my invention I overcome the foregoing difficulties in that my shingle is at all times effectively secured against being blown up by wind and yet is capable of slight movement 85 to accommodate itself to the expanding and contracting movements of the roof structure. This I accomplish by forming in the marginal edges of the flap 12, notches 14 which are 90 preferably more or less elongated in the gen- 100

eral direction of these marginal edges. As shown, the notches 14 are of rectangular configuration but it should be understood, of course, that they may assume other shapes. In any event, however, the notches should have one of their extremities terminated as at 15 a short distance from the extremity of this corner portion of the shingle. The opposite extremities 16 of the notches terminate a short distance outwardly of the line of fold 13.

In conjunction with each shingle constructed as thus far described, I employ a fastening device which, as shown in Figures 1 and 15 3, may comprise a U-shaped member 18, the bridge portion of which is adapted to straddle and overlie the underfolded flap of the shingle and to have its prongs or driving members 19, accommodated for free play 20 within the marginal notches 14 thereof. Manifestly the inclination of the sides of the notches should be such that the prongs of the fastening device will be confined at all times within the notches, so that the flap 25 cannot be dislodged from beneath the bridging portion of the fastener.

If desired the edges 16 of the notches may extend inwardly into the main part of the flap 12 a greater distance than do the edges 30 15 so as to form a saw tooth notch which may in some instances be desirable.

It will be understood, of course, that in applying these shingles to a roof, the shingles of each course are laid with the retroverted flap thereof arranged between converging lateral edges of a pair of shingles in the preceding course, and when the flap has been adjusted to proper position, the fastening device may then be driven into place. The 40 main body of the shingle, as will be apparent, overlies the flap and its associated fastening device and thus conceals the latter and protects it against rapid deterioration.

In some instances I may use a modified 45 form of fastening member as illustrated in Figures 4 and 5. As here shown, the bridging portion of the fastening member 18—a is formed with a central extension 18—b in the shape of a U, and in the same horizontal 50 plane with the end portions of the bridge of this fastening device. When applied, this particular form of fastener is adapted to have its extension 18—b bearing upon the upper surface of the underfolded flap of its 55 associated shingle to thereby further resist displacement of the latter.

In Figure 6 I have shown one way in which the shingles of my present invention may be cut from a sheet of roofing base, as for 60 example the well-known saturated and coated and mineral surfaced roofing. As here illustrated, the sheet of roofing base A travelling through the cutting mechanism in the direction indicated by the arrow, may be 65 severed centrally along the longitudinal line

21 and similarly cut along transverse lines 22. Near the point of intersection 23 of the longitudinal cut 21 with alternate ones of the transverse cuts 22 the sheet may have cut or punched therefrom rectangular openings 24, 70 spaced as shown from the point of intersection 23 and arranged symmetrically with respect thereto and also with respect to the cuts 21 and 22 at this point, thus forming a group of four shingles, each having the marginal 75 notches in its lateral edges. If desired, the sheet may be formed with score marks 25 extending across the adjoining corner portions of the shingles in each group, these score marks being intended to indicate the line 13 80 upon which the shingle is to be thereafter creased or folded as already described.

Having thus fully described the invention, what I claim as new and desire to secure by Letters Patent, is:

1. A shingle of the character described, having one of its corners adapted for retroversion, the converging edges of said corner having notches therein for the accommodation of a securing device, each of said notches 90 having one of its extremities spaced from the line of retroversion of said corner and a laterally extending shoulder at its opposite extremity.

2. A shingle of the character described, 95 having one of its corners folded beneath the main body portion thereof, the converging edges of said underfolded corner having notches therein adapted to accommodate a securing member for holding said corner in 100 retroverted position on a roof, said notches being elongated in the general direction of said edges and having the lower extremities thereof spaced from the line of fold of said corner.

3. A shingle of the character described, comprising a main body portion and a retroverted tab formed at one corner of the body portion, said tab being formed with elongated openings terminating upwardly of the 110 line of retroversion of said tab when the latter is in retroverted position, said openings being formed with spaced abutments and being arranged to accommodate the prongs of a securing device and to confine said tab 115 in retroverted position when the shingle is laid with others on a roof.

FREDERICK C. OVERBURY.
